(57) **CLAIM**

The ornamental design for a “mounting clip,” as shown and described.

DESCRIPTION

FIG. 1 is a front perspective view of a first embodiment of a mounting clip according to my new design;

FIG. 2 is a front view of the mounting clip of FIG. 1;

FIG. 3 is a left side view of the mounting clip of FIG. 1, the right side view being a mirror image of the left side view;

FIG. 4 is a top view of the mounting clip of FIG. 1;

FIG. 5 is a bottom view of the mounting clip of FIG. 1;

FIG. 6 is a back view of the mounting clip of FIG. 1;

FIG. 7 is a bottom rear perspective view of the mounting clip of FIG. 1;

FIG. 8 is a front perspective view of a second embodiment of a mounting clip according to my new design;

FIG. 9 is a front view of the mounting clip of FIG. 8;

FIG. 10 is a left side view of the mounting clip of FIG. 8, the right side view being a mirror image of the left side view;

FIG. 11 is a top view of the mounting clip of FIG. 8; and

FIG. 12 is a bottom view of the mounting clip of FIG. 8.

FIG. 13 is a back view of the mounting clip of FIG. 8; and,

FIG. 14 is a bottom rear perspective view of the mounting clip of FIG. 8.
